UNITED STATES PATENT OFFICE.

WILLIAM BRANAGAN, OF OSWEGO, NEW YORK.

DESIGN FOR AN ASH-SIFTER.

SPECIFICATION forming part of Design No. 30,737, dated May 9, 1899.

Application filed April 16, 1899. Serial No. 713,211. Term of patent 7 years.

To all whom it may concern:

Be it known that I, WILLIAM BRANAGAN, a citizen of the United States, residing at Oswego, in the county of Oswego and State of New York, have invented and produced a new and original Design for Ash-Sifters, of which the following is a specification, reference being had to the accompanying drawings, forming part thereof, and in which—

Figure 1 is a side view thereof. Fig. 2 is an end view thereof.

As shown in the accompanying drawings, the leading or material feature of my design consists of an ash-sifter body *a*, spherical in form and having upon opposite sides a disk *b*, and trunnions *c*, passing through the body

and through said disk, one end terminating in a handle *d*.

e is a cover, located upon one side, conforming to the general outlines of the body. ²⁰

Having described my invention, what I claim, and desire to secure by Letters Patent, is—

The design for an ash-sifter, substantially as herein described and shown. ²⁵

In witness whereof I have hereunto set my hand this 10th day of April, 1899.

WILLIAM BRANAGAN.
